UNITED STATES PATENT OFFICE

2,544,981

HEATING SYSTEM

Leslie A. Buell, Holly, Mich.

Application September 19, 1947, Serial No. 775,035

2 Claims. (Cl. 237—56)

1

The present invention relates to a heating system and it consists in the combinations, constructions and arrangements of parts herein described and claimed.

It is an object of the present invention to provide a heating system especially adapted for use in buildings, particularly dwelling houses, having no basements.

A further object of the invention is the provision of novel means for concealing the supply pipes furnishing water or steam to a radiator in a system of the character set forth.

Another object of the invention is the provision of novel removable blocks to provide access to the concealed pipes in a device of the character set forth.

A further object of the invention is the provision of novel means for concealing the supply pipes aforesaid where they pass beneath or adjacent a door.

Other and further objects of the invention will become apparent from a reading of the following specification taken in conjunction with the drawings, in which:

Figure 1 is a vertical sectional view of a building having an embodiment of the invention therein,

Figure 2 is a sectional view taken along line 2—2 of Figure 1,

Figure 3 is a prospective view of an element of the invention,

Figure 4 is an enlarged sectional view taken along line 4—4 of Figure 2,

Figure 5 is an enlarged sectional view taken along line 5—5 of Figure 1, and

Figure 6 is a perspective view of another element of the invention.

Generally, the system provides for a shallow trough to be placed at the juncture of the floor and wall of a building having no basement. In the trough is laid the supply pipe for a series of radiators. At the unions of the pipe special removable blocks are provided so that access may be had thereto and an especially designed block is provided for covering the pipe wherever it passes a point adjacent a door.

Referring now more particularly to the drawings, there is shown therein a building 10 having a floor 11 of cement or the like and walls 12 which may be of cinder block or other constructions. The inner wall is composed of furring 13 over which plasterboard 14 is placed and it will be seen, by reference to Figure 4, that the furring and plasterboard terminate at a distance above the floor 11. The remainder of the distance to

2

the floor is covered by a mopboard 15 which is fastened to the plasterboard and furring by means of screws 16. Adjacent the wall 12 and below the inner wall, the floor 11 is cut away to form a trough 17 in which are laid the supply pipes 18 of the heating system. The supply pipes 18 are connected by means of unions 19 and the floor 11 is cut away adjacent such unions at an angle to the vertical, as indicated at 20, and a shoulder 21 is provided at the lower end of such cut. Into such cutaway a portion of block 22 having a lower contour adapted to fit the surface 20 and 21, as indicated at 23 and 24, respectively, is adapted to be placed.

15 Radiators 25 are connected by pipes 26 and 27 to the supply pipes 18 and are provided with control valves 29.

Where the supply pipe 18 passes through the trough 17 adjacent a door 30 the same is covered 20 by a cement block 31 having inverted U-shaped passage 32 in the lower side thereof.

In operation, it will be apparent that the radiator 25 in this system may be supplied with hot water utilizing a thermostatically controlled 25 booster pump to force water therethrough and that, upon the pump becoming inoperative, the valve 28 will cut off the flow thereto. When desired, the valve 29 may be manually operated to cut off such supply.

It will be seen that the supply pipes are fully 30 hidden from view even though the building be without a basement for the mounting of such pipes in the conventional manner. It will also be seen that, whenever necessary, a wrench 33 may be utilized upon the unions 19 by the simple removal of a block 22 and its adjacent baseboard 16 to provide access to such union. It will also be seen that the blocks 31 may be cemented over to provide more complete concealment of the supply pipes.

40 While but one form of the invention has been shown and described herein, it will be readily apparent to those skilled in the art that many minor modifications may be made without departing from the spirit of the invention or the scope of the appended claims.

What is claimed is:

1. A heating system for houses comprising, in combination, a wall, a floor having a trough adjacent the base of said wall, radiator supply pipes in said trough, union joints in said supply pipe; said floor having cutaway portions being provided with vertical sides, a relatively large angularly extending bottom and a relatively small 50 angularly and oppositely extending shoulder con-

of, and blocks removably mounted in said cut-away portions, said blocks when seated in said portions completing the cross sectional silhouette of said floor and trough.
